(57) **CLAIM**

The ornamental design for a tent fly, as shown and described.

DESCRIPTION

FIG. 1 is a perspective view of a tent fly shown in a tent environment;

FIG. 2 is a top view thereof; and,

FIG. 3 is a bottom view thereof.

The dashed lines depict portions of the tent fly that form no part of the claimed design. The tent fly includes symbolic break lines along its length drawn in broken lines. The broken lines and the area between the break lines form no part of the claimed design.
